Inventor:

Geo B Kirkham

United States Patent Office.

GEORGE BYRON KIRKHAM, OF NEW YORK, N. Y.

Letters Patent No. 70,444, dated November 5, 1867.

IMPROVED WINDOW-FASTENING.

The Schedule referred to in these Letters Patent and making part of the same.

TO ALL WHOM IT MAY CONCERN:

Be it known that I, GEORGE BYRON KIRKHAM, of 167 East Thirty-Third street, city, county, and State of New York, have invented a new and useful Improvement in a Window-Fastening, which I term a Window-Guard; and I do hereby declare the following to be a full, clear, and exact description of the same, sufficient to enable one skilled in the art to which the invention appertains to make use of it, reference being had to the accompanying drawings, which form a part of this specification, and in which—

Figure 1 represents an inside view of the fastening, that is, the side which rests against the window or door, and to which it is secured by screws or any suitable means.

Figure 2 shows separately the double-toothed bolt B.

Figure 3 is an under view of the finger-slide C, D being the depressed part that rests on the bolt B.

Figure 4 represents the body of the fastening, with the bolt and slide removed to show the key-hole F and the catch E which the key acts against.

Figure 5 represents the key.

This improvement is designed to produce a fastening which shall be simple, yet strong and efficient, such as can be applied to windows, doors, &c., and when desired can be locked and unlocked either from the inside or outside.

In fig. 1 the bolt B is shown as moving to the right or left, according as the slide C is pressed up or down, the acute angles of their bearings causing that movement. This bolt B has a double-toothed point, which, when it is pushed out, presses against the framework of the window or door, and prevents them from being moved or opened. On the lower part of the slide C is a ridge, G, shown in fig. 3, which ridge engages with a catch, E, in fig. 4, and this catch E must be pushed to one side when the slide is raised. This is accomplished by the key, fig. 5, which is shoved through the key-hole F, and when turned the point of the key H pushes the catch E to one side so the slide C can be raised, thus opening the whole fastening.

Having described my invention, what I claim therein as new, and desire to secure by Letters Patent, is—

I claim the fastening complete with its several parts, the body A, the double-pointed bolt B, the slide C, the catch E, and the key, as described and represented.

GEO. B. KIRKHAM.
